APPARATUS FOR PERMANENTLY WAVING
HAIR

Ralph M. Keele, San Francisco, Calif., assignor,
by direct and mesne assignments, to Keelmo
Co., San Francisco, Calif., a corporation of
California

Application May 16, 1936, Serial No. 86,128

23 Claims. (Cl. 132—36)

This invention relates to an apparatus for so-called "permanent" waving hair on the human head, and particularly pertains to an improved apparatus for practicing what is known as the 5 Croquignole method of "permanent" waving.

In prior Croquignole methods of waving hair, the hair is treated with a softening solution and is then divided into flat strands and a protector pad and clamp is applied to the base of each 10 strand closely adjacent to the scalp to protect the scalp and to hold the strand for further treatment. Each strand of hair is then wound flatwise from its free end to the clamp on a curler spindle which is then usually connected with the 15 clamp and turned to place the hair under tension. A moisture pad with an outer impervious cover is then wrapped over the wound strand, and heat is applied thereto to a degree sufficient to vaporize the moisture and cause it to penetrate the wound 20 strand and effect the wave. When the heat is to be generated electrically, a heater embodying electrical heating elements is applied over the wrapped hair to apply heat thereto. When the heat is generated by exothermic reaction, the 25 exothermic material is in the form of a pad and is wrapped about the wound strand and the whole is enclosed in a housing usually termed a heater.

The process of waving hair and apparatus for 30 practicing it just described is the most commonly employed and has a number of shortcomings. These shortcomings are principally due to the provision of the pads and clamps which, due to their length and thickness, obviously prevent 35 the wave from being spaced a uniform short distance from the scalp. Further, the application of such protector pads and clamps and the subsequent application of moisture wrappers and exothermic pads consumes considerable of the operator's time, and the weight thereof on the head 40 adds to the discomfort of the waving operations.

It is the principal object of my present invention to provide an improved and highly efficient apparatus for use in practicing the Croquignole 45 method of "permanent" waving, which apparatus effects a superior form of wave and overcomes the shortcomings of the apparatus heretofore employed, in that it simplifies the operations required to effect a wave so as to minimize the time required to wave a head of hair, permits 50 the application of a greater number of curlers to be applied to a head of hair than can be applied by use of prior methods and apparatus so that a wave may be produced which will be uniformly spaced and comparatively close to the

scalp, and which apparatus reduces the weight applied to the head so as to reduce the discomfort of the waving operations.

One form which the invention may assume is exemplified in the following description and illustrated by way of example in the accompanying drawing, in which:

Fig. 1 is a perspective view of a heater unit embodying the preferred form of my invention.

Fig. 2 is a perspective view of the casing portion of the heater unit.

Fig. 3 is an enlarged transverse sectional view through the heater unit taken on line III—III of Fig. 4.

Fig. 4 is an enlarged central longitudinal section through the heater unit taken on line IV—IV of Fig. 3.

Referring more particularly to the accompanying drawing, 10 indicates a heater unit forming the major part of the apparatus constituting the 20 subject matter of my invention. This heater unit includes a hollow casing 11, most clearly illustrated in Figs. 2 and 3, which is substantially rectangular in outline with a thickness somewhat less than its width. The marginal side edges of 25 this casing 11 are semi-cylindrical and the curvature of both the exterior and interior of such edges is carried out as illustrated to give the effect of two hollow cylinders arranged with their axes parallel and with their adjacent side walls 30 intersecting along a line which is at a distance from the centers of said cylinders which is just slightly less than half the diameter of the cylinders. Thus, the interior of said casing forms a 35 substantially cylindrical and elongated heating chamber 12 and a substantially cylindrical and elongated curling chamber 14, which chambers are arranged side by side in parallelism and in direct communication with each other through the elongated narrowed opening 15 between 40 them.

The end walls 16 of the casing are substantially flat although they mold into the marginal edges at one side of the casing as indicated. The end walls and the side walls of the casing 11 are integrally formed of resilient vulcanized rubber. Each of the end walls is formed with a circular opening 17, which openings are in axial alignment and disposed concentric with relation to the curling chamber 14. Between these openings and 50 the adjacent marginal edges of the casing, the end walls are centrally divided as at 18 and said adjacent marginal edge is correspondingly centrally and longitudinally divided so that the portions of the casing at opposite sides of the divi- 55

sion constitutes two complementary clamping lips 18a and 18b, which may be separated in a direction at right angles to the axis of the curler chamber so that the casing may be fitted over a curler spindle as will be hereinafter described.

The casing 11 of the heater unit is enclosed in a heater unit frame 19 which comprises two complementary rigid jaw sections 20, which are spaced apart to receive the casing 11 therebetween.

10 These jaws are preferably formed of pressed sheet metal or molded Bakelite, or a like substance having sufficient strength and rigidity, and are of a formation that they snugly nest over the sides of the casing as illustrated. At the side of the casing 11 opposite the clamping lips thereof, the jaw sections 20 of the frame are each formed with a projecting grip member 21, which are located substantially midway between the opposite ends of the jaw sections. Substantially at

20 the junction between the grip members 21 and the jaw sections 20, the latter are formed with inturned complementary hinge lugs 22 which are hinged together to articulately connect the jaws so that the latter may be relatively moved.

25 The side edges of the jaws opposite the hinge connection therebetween are curved inwardly and are detachably united with the clamping lips 18a and 18b of the casing 11. From the drawing it will be noticed that at the edges of these clamping lips they are longitudinally grooved to receive the inturned edges of the jaw sections 20, and complementary connecting means are formed on these inturned edges and in the grooves to form a detachable connection between the lips and 30 jaw sections. This connection is such that when the jaw sections are relatively moved, the clamping lips of the casing will be moved in unison therewith. Consequently, by moving the two grip members 21 toward each other, the clamping lips 35 of the casing will be spread apart sufficiently to enable the casing to be positioned over a curler.

Spring means 23 is provided between the grip members 21 which normally tends to maintain 40 the clamping lips of the casing in clamping relation through the medium, of course, of the rigid jaw sections 20.

At the outer side of each jaw section 20 I provide a spacer clamp member 24 formed of sheet 45 material of suitable qualities, which spacer clamp members lie closely adjacent to the outer surfaces of the jaws 20 and which extend outwardly a spaced distance from the inturned edges of the jaw members 20. At this point the spacer clamp 50 members are inturned to provide clamping edges 25 which are arranged parallel to and at a spaced distance outwardly from the clamping lips of the casing 11. It will be noticed that the clamping edges 25 of the spacer clamp members are provided with detachable rubber covers as illustrated.

55 The spacer clamp members are slightly resilient so that the clamping lips 18a and 18b of the casing 11 and the spacer clamping edges 25 will both tightly grip a strand of hair regardless of 60 whether the thickness of the strand of hair is greater at the point where it is gripped by the spacer clamp than at the point where it is gripped by the clamping lips of the casing 11.

For use in connection with this heater unit I 65 provide a curler spindle 26 most clearly illustrated in Fig. 4. This curler spindle has a curling surface which is a hyperboloid of revolution with its larger diameter at its ends. At each extremity the curler spindle 26 is formed with an enlarged circular head 27, between which heads and the

curling surface the spindle is formed with bearing pins 28 which are reduced in diameter relative to the end of the adjacent curling surface. The diameter of these bearing pins 28 is just slightly greater than the circular openings 17 5 formed in the end walls of the casing, so that when the casing 11 is arranged over the curler, the edges of the circular openings 17 will register with the bearing pins 28 and yieldably grip them so as to maintain the curler concentrically within the curling chamber and prevent the curler from rotating. It should be stated that this yieldable gripping action between the edges of the openings 17 and the bearing pins 28 enables the curler to be turned by manually gripping one end 10 thereon to take up any slack in the hair after the curler has been positioned and gripped within the casing 11.

Pivoted at one end to the curling surface of the spindle 26 is a clamping tongue 29 arranged to 20 lie closely adjacent to the curling surface of the curler spindle to enable the end of a strand of hair to be clamped to the spindle at the beginning of the winding operation.

I contemplate using heat generated by chemical reaction within the heating chamber to effect the permanency of the wave. For this purpose I employ the type of curler spindle shown in Fig. 4 which is longitudinally bored and ports 26a extend from this bore through the curling surface 30 to enable hot vapors to pass from within the casing through the curler spindle, which expedites the heating of the curler spindle and equalizes the heat throughout the wound hair.

To generate heat by chemical reaction, I provide an exothermic heating element 31 which is a cylindrical cartridge of a length and diameter that it may be snugly fitted within the heating chamber of the casing. I prefer that this chemical heating element consist of a core of suitable 40 chemical, such as calcium oxide, wrapped in a perforated sheet of metal foil, over which foil is a layer of absorbent material, the same in turn being enclosed in a cover impervious to moisture. Just prior to its being used, the parchment or 45 impervious wrapper is removed and the cartridge is dipped in fluid and placed in the heating chamber of the casing. The reaction resulting from the application of moisture to the calcium oxide or charge generates sufficient heat within the 50 casing to effect the permanency of the wave.

In operation of my apparatus, it is constructed substantially as illustrated and described. The hair is treated with the proper solution, the strength of which determines the tightness of 55 the wave. The hair is then divided into strands and each strand is wound on a curler 26 from its outer end to the scalp. A heating unit is then applied over the curler with the circular openings 17 receiving the bearing pins 28 and securing the 60 curler with the hair wound thereon concentrically within the curling chamber of the casing 11. The exothermic heating element dipped in the same solution that the hair was treated with would 65 first be inserted into the heating chamber of the casing.

It is obvious that as soon as the heating unit is applied to the curler that the strand will be tightly clamped just beneath the curler by the clamping lips of the casing 11 urged toward each 70 other by the spring-pressed jaws comprising the frame of the unit. Likewise, the spacer clamping edges 25 will tightly grip the strand closely adjacent to the scalp, maintaining a spacing between the scalp and the clamping lips of the casing. 75

This provides a double seal to prevent any escaping hot vapors from contacting the scalp.

It is obvious that due to the provision of these clamping devices formed as an integral part of the heater unit, that the operations of previously applying protector clamps and pads has been eliminated, thus effecting a considerable saving of the operator's time. Likewise, by eliminating the use of protector clamps and pads, the strands 10 of hair are not bunched at the scalp so that the wave will be spaced a uniformly close distance to the scalp, thus giving a more natural appearance and effect.

It should also be pointed out that my heating unit with its clamping mediums will be considerably lighter in weight than the combined weights of prior heaters, clamps and protector pads, consequently lessening the discomfiture of the "permanent" waving operations.

20 After the heating unit has been applied to the curler as previously described, the curler may be slightly turned by manually gripping one of the heads thereon to take up any slack on the hair wound thereon. The yielding gripping action between the edges of the openings 17 and the bearing pins 28 on the curlers will maintain the curler in a set position.

The heat generated is, of course, sufficient to vaporize the moisture and causes the hot vapors 30 to pass through the hair into the curler. This element will, of course, rise to an equivalent temperature so that the heat applied will be uniform, thus effecting an excellent wave.

The heater unit is left on until the same is approximately cool, at which time the hair has been properly steamed. The heater is then removed by gripping the grip members and spreading the jaw members of the frame. The curler is then unwound and detached from the hair and 40 the wave is ready for setting.

Here also an operation is saved in that the operator need not remove any clamps or protectors from the head, consequently expediting the entire operation of giving a "permanent" wave to a head 45 of hair.

From the foregoing it is obvious that I have provided an improved and highly efficient apparatus for use in practicing the Croquignole method of "permanent" waving, by which apparatus I am enabled to produce a superior form 50 of wave. Likewise, it is apparent that my improved apparatus overcomes the shortcomings of prior apparatus heretofore employed in that it reduces and simplifies the operations required to effect such a wave and therefore minimizes the time required to wave a head of hair.

Further, I desire to point out that by the use of my apparatus, a greater number of curlers may be applied to a given head of hair than could be 60 applied by use of prior methods and apparatus so that the wave which I produce will be closely and uniformly spaced from the scalp.

Further, by use of my apparatus the weight on the head is less than the weight applied by prior 65 methods, and consequently minimizes the discomfiture of the "permanent" waving operations.

While I have shown the preferred form of my apparatus, it is to be understood that various changes may be made in its construction by those skilled in the art without departing from the spirit of the invention, as defined in the appended 70 claims.

Having thus described my invention, what I claim and desire to secure by Letters Patent is:

75 1. A hair waving apparatus comprising a heater

unit including a hollow casing, the interior of which forms a heating chamber and a curling chamber lying side by side in parallelism and in direct communication, said casing being divided longitudinally of the curling chamber to form a 5 pair of opposed clamping lips at one side of said chamber which may be spread apart to open the curling chamber for the insertion of a curler spindle, said casing being formed of resilient material, and an exothermic heating element removable fitting within said heating chamber, said element being insertable into said chamber through said division of the curling chamber.

2. A hair waving apparatus comprising a heater unit including a hollow casing, the interior of which forms a heating chamber and a curling chamber lying side by side in parallelism and in direct communication, said casing being divided longitudinally of the curling chamber to form a 10 pair of opposed clamping lips at one side of said chamber which may be spread apart to open the curling chamber for the insertion of a curler spindle, said casing being formed of resilient material, a pair of articulately connected rigid jaw members embracing said casing and connected thereto at said lips and normally urging said lips toward each other, and an exothermic heating element removable insertable in said heating chamber.

3. A hair waving apparatus comprising a heater unit including a hollow casing, the interior of which forms a spaced communicating heating chamber and a curling chamber, said casing having aligned openings at opposite ends of said curling chamber and substantially centrally thereof, 35 and a curler spindle having ends adapted to be received in said openings whereby it will be supported coaxially within said chamber, and an exothermic heating element removable fitting the interior of said heating chamber and enclosed 40 thereby except that it is in open communication with the curling chamber.

4. A hair waving apparatus comprising a heater unit including a hollow casing, the interior of which casing forms a heating chamber and a 45 curling chamber lying side by side in parallelism and in direct communication, said casing having aligned openings at opposite ends of the curling chamber, a curler spindle having ends adapted to be received in said openings whereby the curler 50 will be supported substantially coaxially within said curling chamber, said spindle having vapor conveying passages therethrough, and an exothermic heating element disposed in said heating chamber.

5. A hair waving apparatus comprising a heater unit including a hollow casing, the interior of which forms an elongated heating chamber and an elongated curling chamber arranged side by side in parallelism and in direct communication, 60 said casing having aligned openings in its ends substantially coaxially of said curling chamber, a bored curler spindle having ends adapted to be yieldingly gripped in said openings whereby it will be supported coaxially within said curling 65 chamber, said spindle having ports extending radially from said bore through said spindle, said casing being divided longitudinally of the curling chamber at the side thereof opposite the heating chamber forming a pair of clamping lips which 70 may be spread apart to permit insertion of said curler spindle, and an exothermic heating cartridge removable fitting said heating chamber.

6. A hair waving apparatus comprising a heater unit including a hollow casing formed of molded 75

- rubber, the interior of said casing forming spaced intercommunicating heating and curling chambers lying side by side, said casing having aligned openings formed at opposite ends of the curling chamber and substantially coaxially thereof, a curler spindle fitting within said curling chamber and adapted to be gripped adjacent its ends within said openings, said casing being divided at the side of the curling chamber opposite the heating chamber and between said openings, a pair of articulately connected members connected with said casing at opposite sides of said division to open said casing whereby the same may be arranged over a wound strand of hair on said spindle, and an exothermic heating element adapted to be inserted through said division and into said heating chamber prior to the arranging of the casing over a wound strand of hair on the curler spindle.
- 5 7. Apparatus for use in permanent waving, in conjunction with a curler upon which a strand of hair is wound, said apparatus comprising a jacket formed of resilient rubber, and including two opposed flexible walls capable of flexing to facilitate application of the jacket about the curler, a holder including two opposed relatively movable members normally urged together and attached to the flexible walls of the jacket, said jacket being so dimensioned that a compartment is formed therein extending longitudinally of the curler and the one side of the same, and a chemical heater packet removably disposed within said compartment and adapted to be moistened to generate steam.
- 10 8. In apparatus for use in permanent hair waving, in conjunction with a protector which is clamped about a strand of hair and a curler which is carried by the protector and parallel thereto, a one-piece jacket formed entirely of resilient rubber adapted to removably embrace the curler with the ends of the curler extending from the ends of the jacket, the jacket having two opposed longitudinal edges adapted to be interposed between the curler and the protector on opposite sides of the hair strand extending from the protector to the curler, whereby the jacket is sealed about the curler to form a steam chamber, said jacket, on that side of the curler remote from the protector, being dimensioned to form an interior compartment extending parallel to the curler and adjacent one side of the same, and a chemical heater packet removably disposed within said jacket and adapted to be moistened to generate steam.
- 15 9. In hair waving apparatus, a jacket formed with two opposed flexible walls formed of resilient rubber and adapted to be spread apart, said jacket being adapted to be clipped over a curler on which hair is wound, said jacket being dimensioned to form a compartment extending longitudinally of the curler and adjacent one side of the same, said compartment being closed by end walls formed integral with the side walls, and a chemical heater packet removably disposed within said compartment, said packet being retained within said compartment by the resiliency of said walls, and forming a generator of steam when moistened, said jacket serving to direct steam evolved from the packet about the wound hair.
- 20 10. Apparatus for use in permanent hair waving in conjunction with a curler upon which a strand of hair is wound, comprising a jacket formed of resilient rubber, and including two opposed flexible walls capable of flexing to facilitate application of the jacket about the curler, said jacket being so formed, that when applied to the curler, a compartment is formed extending longitudinally of the curler and along one side of the same, the ends of said compartment being closed, the lower side of said compartment being in communication with that portion of the jacket occupied by a curler, and a chemical heater packet removably disposed within said compartment, said packet being adapted to be moistened to form a generator of steam.
- 25 11. A hair waving apparatus comprising a heater unit including a hollow casing, the interior of which forms a curling chamber, said casing having aligned openings at opposite ends of said chamber and substantially centrally thereof, and a curler spindle having ends adapted to be received in said openings whereby it will be supported coaxially within said chamber.
- 30 12. A hair waving apparatus comprising a heater unit including a hollow casing, the interior thereof forming an elongated curling chamber, said casing having aligned openings at opposite ends of said chamber and substantially coaxially thereof, a curler spindle having ends adapted to be received in said openings whereby it will be supported coaxially within said chamber, said casing being divided longitudinally of said curling chamber and centrally of said openings whereby the portions of said casing on opposite sides of the division may be spread apart to enable insertion of said curler spindle, a pair of articulately connected rigid jaw members embracing said casing and connected therewith at opposite sides of said division thereof to open and close the same.
- 35 13. A hair waving apparatus comprising a heater unit including a hollow casing formed of vulcanized rubber, the interior of which forms an elongated curling chamber, said casing having aligned openings at opposite ends of said chamber and substantially coaxially thereof, a curler spindle having ends adapted to be received in said openings whereby it will be supported substantially coaxially within said chamber, said casing being divided longitudinally of the curling chamber and substantially centrally of the openings at one side thereof to form a pair of opposed clamping lips, a frame embracing said casing and including a pair of rigid side sections articulately connected, said side sections being connected with said casing at said clamping lips, and spring means associated with said side sections constantly tending to urge said clamping lips toward each other.
- 40 14. A hair waving apparatus comprising a heater unit including a hollow casing, the interior of which forms a charging chamber and a curling chamber lying side by side in parallelism and in direct communication, said casing being divided longitudinally of the curling chamber to form a pair of opposed clamping lips at one side of said chamber which may be spread apart to open the curling chamber for the insertion of a curler spindle, said casing being formed of resilient material, a pair of articulately connected rigid jaw members embracing said casing and connected thereto at said lips and normally urging said lips toward each other.
- 45 15. A hair waving apparatus comprising a heater unit including a hollow casing, the interior of which forms a curling chamber, said casing having aligned openings at opposite ends

of said chamber and substantially centrally thereof, and a curler spindle having ends adapted to be yieldingly gripped in said openings whereby it will be supported coaxially within said 5 chamber.

16. A hair waving apparatus comprising a heater unit including a hollow casing of flexible material, the interior thereof forming an elongated curling chamber, said casing having 10 aligned openings at opposite ends of said chamber and substantially coaxially thereof, a curler spindle having ends adapted to be yieldingly gripped in said openings whereby it will be supported coaxially within said chamber, said casing 15 being divided longitudinally of said curling chamber and centrally of said openings whereby the portions of said casing on opposite sides of the division may be spread apart to enable insertion of said curler spindle, a pair of articulately connected rigid jaw members embracing said casing and connected therewith at opposite sides of said division thereof to open and close the same.

17. A hair waving apparatus comprising a heater unit including a hollow casing, the interior of which forms a charging chamber and a curling chamber lying side by side in parallelism and in direct communication, said casing being divided longitudinally of the curling chamber 20 to form a pair of opposed clamping lips at one side of said chamber which may be spread apart to open the curling chamber for the insertion of a curler spindle, a pair of articulately connected rigid members embracing said casing 25 and connected thereto at said lips and normally urging said lips toward each other, means for charging said charging chamber with moisture, and means for generating heat within the interior of said casing.

18. A hair waving apparatus comprising a heater unit including a hollow casing, the interior of which forms a curling chamber, said casing having aligned openings at opposite ends of said chamber and substantially centrally thereof, and a curler spindle having ends adapted to be received in said openings whereby it will be supported coaxially within said chamber, and a heating element disposed within the casing.

19. A hair waving apparatus comprising a heater unit including a hollow casing, the interior of which forms a charging chamber and a curling chamber lying side by side in parallelism and in direct communication, said casing being divided longitudinally of the curling chamber 40 to form a pair of opposed clamping lips at one side of said chamber which may be spread apart to open the curling chamber for the insertion of a curler spindle, a pair of articulately connected rigid members embracing said casing 45 and connected thereto at said lips and normally urging said lips toward each other, a moisture absorbent charging cartridge fitting said charging chamber, and means for generating heat within said casing.

20. A hair waving apparatus comprising a

heater unit including a hollow casing, the interior of which casing forms a charging chamber and a curling chamber lying side by side in parallelism and in direct communication, said casing having aligned openings at opposite ends of the 5 curling chamber, a curler spindle having ends adapted to be received in said openings whereby the curler will be supported substantially coaxially within said curling chamber, a moisture charging cartridge removably fitting said charging chamber, and means for generating heat within the interior of said casing.

21. A hair waving apparatus comprising a heater unit including a hollow casing, the interior of which forms an elongated charging 15 chamber and an elongated curling chamber arranged side by side in parallelism and in direct communication, said casing having aligned openings in its ends substantially coaxially of said curling chamber, a curler spindle having ends 20 adapted to be yieldingly gripped in said openings whereby it will be supported coaxially within said curling chamber, said casing being divided longitudinally of the curling chamber at the side thereof opposite the charging chamber 25 forming a pair of clamping lips which may be spread apart to permit insertion of said curler spindle, a moisture charging cartridge removably fitting said charging chamber, and means for generating heat within the interior of said casing.

22. A hair waving apparatus comprising a heater unit including a hollow casing, the interior of which forms a charging chamber and a curling chamber lying side by side in parallelism and in direct communication, said casing being 30 divided longitudinally of the curling chamber to form a pair of opposed lips at one side of said casing which may be spread apart to open the curling chamber, a pair of articulately connected members connected to said casing and normally 35 urging said lips toward each other but capable of operation to spread said lips apart to open the curling chamber, an exothermic cartridge capable of insertion into said charging chamber between said lips and through said curling chamber, and a curler spindle for insertion between said lips 45 substantially coaxially of the curling chamber.

23. A hair waving apparatus comprising a heater unit including a hollow casing, the interior of which forms a charging chamber and a curling chamber lying side by side in parallelism and in direct communication, an exothermic cartridge adapted to be inserted into the charging chamber and removably retained therein, said casing being divided longitudinally of the curling chamber at the side thereof opposite the charging chamber to form a pair of opposed lips at one 50 side of said chamber which may be spread apart to open the curler chamber for the insertion of a curler spindle, a pair of articulately connected rigid members connected with said casing and normally urging said lips toward each other but capable of operation to spread said lips apart to 55 open the curling chamber.

RALPH M. KEELE. 60
